(57) **CLAIM**

The ornamental design for a cup holder, as shown and described.

DESCRIPTION

FIG. 1 is a front elevational view of a cup holder showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front-top perspective view thereof;

FIG. 8 is a rear-top perspective view thereof;

FIG. 9 is a bottom perspective view thereof; and,

FIG. 10 is an enlarged portion taken from the circumscribed area marked **10** in FIG. 9.

The cup holder is an article for holding a cup for use in a vehicle or in furniture such as massage chairs, sofas or beds. The broken lines in the figures are included for the purpose illustrating portions of the article which form no part of the claimed design.
